UNITED STATES PATENT OFFICE.

JOHN B. DENNIS, OF OTTUMWA, IOWA.

ATTACHMENT FOR CHECK-WRITERS.

1,161,629.

Specification of Letters Patent. Patented Nov. 23, 1915.

Application filed August 19, 1915. Serial No. 46,394.

To all whom it may concern:

Be it known that I, JOHN B. DENNIS, a citizen of the United States, residing at Ottumwa, in the county of Wapello and State of Iowa, have invented certain new and useful Improvements in Attachments for Check-Writers; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in selector attachments for check writing machines and consists in the provision of a simple and efficient attachment to a checkwriter to facilitate the setting of the type to print certain words, numbers or characters.

The present invention comprises various details of construction, combinations and arrangements of parts which will be herein-after fully described, shown in the accompanying drawings and then specifically defined in the appended claims.

My invention is illustrated in the accompanying drawings, in which:

Figure 1 is a top plan view of a check writer showing my invention as applied thereto. Fig. 2 is a side elevation. Fig. 3 is an enlarged top plan view. Fig. 4 is a bottom plan view of a part of the apparatus. Fig. 5 is a sectional view taken on line 5-5 of Fig. 3, looking in the direction of the arrow. Fig. 6 is a sectional view on line 6-6 of Fig. 3. Figs. 7 and 8 are detail sectional views, partly in elevation, of means for releasing a part of the selector device. Fig. 9 is an enlarged detail view of a tilting member forming a part of the selector mechanism. Fig. 10 is a detail view of a selector bar, and Fig. 11 is a modified form.

Reference now being had to the details of the drawings by numeral, 1 designates the frame of a checkwriter of the rotary type, to which a slotted plate 1^x is fastened, and 2 designate a shaft journaled longitudinally in the frame, mounted in suitable bearings therein and having a gear wheel 3 at one end in mesh with a gear wheel 4 fixed to the shaft 5, having a crank handle 6, and its other end has a beveled gear 7 which is in

mesh with a gear 8 fixed to the shaft 9 which is journaled in suitable bearings in the bracket arm 10. A second bracket arm, designated by numeral 11, is mounted upon the other end of the frame and carries a shaft 12 in suitable bearings about which a grooved pulley 13 is journaled, and a sprocket wheel 14 is fixed to the shaft 9. Pins or teeth 15 project from the circumference of the sprocket wheel, and 16 designates an endless tape or band, made preferably of metal and having lugs 17 projecting therefrom at intervals, the distance between the lugs being preferably equal to the circumference of the sprocket wheel upon which they are mounted.

A yoke, designated by numeral 18, is attached to the carriage 19 and which carriage actuates the type of the checkwriter, not shown, and which forms no part of the present invention, and an arm 20 projecting from said yoke extends through a slot 21 in the split tubing 22 and a coiled spring 23 bears at one end against the face of the arm 20 and its other end against the end of the tube in which it is mounted, the purpose of said spring being to normally hold said yoke and carriage at its farthest limit at starting position in one direction. Said yoke carries a latch 24, a detail view of which is shown in Fig. 9 of the drawings, and which is mounted upon a pivotal pin 25 passing through the aperture 26 and which pin is mounted upon a laterally projecting portion 18^x of the yoke, as shown clearly in Figs. 5 and 6 of the drawings. A coiled spring 27 is mounted in a recess in the upper edge of the yoke and bears against one end of the latch and tends to hold the same in the position shown in solid lines in Fig. 6 of the drawings.

Upon reference to Fig. 9 of the drawings, it will be noted that said latch has a rectangular outlined opening 28 formed therein for the reception of the contracted end 29 of the lateral projection 18^x of the yoke. The extreme free end of the latch is bent at an angle forming a cam projection 24^x, provided for a purpose which will be herein-after described.

Upon reference to Fig. 6 of the drawings, it will be noted that the upper edge of the lateral projection 18^x of the yoke has a recess 30 adapted to receive the band 16 and projecting from the under surface of the 116

projection 18^x is a rounded projection 31, shown clearly in Fig. 9, and which is normally positioned in the path of the lugs 17 upon the band 16 and against which said lugs contact as the band travels about the sprocket wheel and pulley, serving to cause the carriage to be moved forward. A pawl 32 is pivotally mounted upon a pin 33 carried by said yoke and extends through a slot 50 in the plate 1^a, as shown clearly in Figs. 5 and 6 of the drawings, and turns idly in one direction and is prevented from tilting in the opposite direction by its upper end coming in contact with the edge of the yoke upon which it is mounted. Selector bars 34 are mounted side by side and adapted to have sliding longitudinal movements, as shown in Fig. 3, and each bears a numeral or word as shown and the outer end of each is preferably provided with a recess 39 adapted to receive an instrument to facilitate the pushing in of the bar to the position shown in Fig. 3, so that the inner end of said selector bar will be positioned in the path of the pawl 32, said projecting portion of the bar serving as a stop to arrest the return movement of the carriage after the pawl upon the yoke has passed by, turning idly over the bar as the carriage is driven forward by the endless band on the sprocket wheel.

Springs, designated by numeral 40, are fastened at corresponding ends to the angled bars 41 fastened to the plate 1^a and to the pins 42, said pins being secured to the selector bars 34 and guided in the slots 43.

In Fig. 11 of the drawings, I have shown a slight modification, in which the selector bar 45 is provided with a hole 47 in which an instrument may be inserted, forming means whereby said selector bar may be moved longitudinally independent of the spring.

In operation, the operator by pushing in upon one or another of the selector bars may cause its inner end to project beyond the others and in the path of the pivotal latch and cam projection upon the latter. This being done, the operator by giving the crank a revolution may cause the sprocket wheels to rotate through the medium of the endless band mounted thereon and, as a lug 17 comes in contact with the marginal edge of the latch, it will cause the carriage and the yoke secured thereto to move forward. When the pivotal pawl 32 comes in contact with the projecting end of the selector bar, which is held at its farthest limit until after the carriage is actuated to its limit in one direction, said yoke will turn idly, allowing the pawl to pass the projecting end of the selector bar and the cam projection upon the latch coming in contact with the selector bar will cause the latch to tilt to allow the lug upon the band to pass by the

latch, thus releasing the yoke from the lug upon the band and the coiled spring 23 will tend to return the carriage toward its starting position but its movement will be arrested by the pivotal pawl 32 coming in contact with the selector bar which is held in its path. The apparatus thus being set for printing of the desired numeral or word upon the check, upon the completion of the turning of the crank handle. The selector bar is then released, if held by a spring at its farthest forward position or withdrawn if the modified form shown in Fig. 11 is employed, and the spring which is attached to the carriage will return the same to its starting position.

What I claim to be new is:—

1. A selector device for checkwriters, comprising a spring-pressed carriage, a yoke fastened thereto, a movable latch having a projection and a pawl pivotally mounted upon said yoke, an endless band and means for moving the same, said band having a lug adapted to contact with the latch to move the carriage with the band, a selector bar movable in the path of said pawl and projection of the latch and against which the pawl is adapted to contact and turn idly thereover as the yoke is moved in one direction, the latch engaging the selector bar causing the carriage to be released from the band, said pawl in its movement with the carriage in a reverse direction adapted to engage the selector bar to arrest the movement of the carriage.

2. A selector device for checkwriters, comprising a spring-pressed carriage, a yoke fastened thereto, a spring-pressed latch and a pivotal pawl mounted upon said yoke, an endless band and means for moving the same, said band having a lug adapted to contact with the latch to move the carriage with the band, a selector bar movable in the path of said pawl and lug of the latch, and against which the pawl is adapted to contact and turn idly thereover as the yoke is moved in one direction, the latch engaging the selector bar causing the carriage to be released from the band, said pawl in its movement with the carriage in a reverse direction adapted to engage the selector bar to arrest the movement of the carriage.

3. A selector device for checkwriters, comprising a spring-pressed carriage, a yoke fastened thereto, a spring-pressed latch and a pivotal pawl mounted upon said yoke, said latch having a rounded projection, a selector bar movable in the paths of said pawl and rounded projection, an endless band, means for moving the same, and lugs upon the band at intervals adapted to contact with the latch, said pawl adapted to turn idly over the selector bar as the pawl moves in one direction and the latch designed to be released by contact with the

selector bar, thus allowing the carriage to return under spring action to a limit determined by the pawl coming in contact with the selector bar on its return movement.

5 4. A selector device for checkwriters, comprising a spring-pressed carriage, a yoke fastened thereto, a spring-pressed latch pivotally mounted upon said yoke, the latter being recessed upon its upper edge, the latch 10 over said recess having a rounded projection and also a cam projection, a pivotal pawl mounted upon said yoke, an endless band movable through said recess and provided with lugs adapted to contact with the 15 rounded projection of the latch, the latter being provided with a downwardly projecting portion, and selector bars movable in the paths of said rounded projection of the latch and of said pawl, the latter adapted to turn 20 idly over the selector bar as the pawl moves in one direction and the latch designed to be released by contact with the selector bar, thus allowing the carriage to return under spring action to a limit determined by the 25 pawl coming in contact with the selector bar on its return movement.

5. A selector device for checkwriters, comprising a spring-pressed carriage, a yoke fastened thereto, a spring-pressed latch pivotally mounted upon said yoke, the latter being recessed upon its upper edge, the latch 30 over said recess having a rounded projection, a pivotal pawl mounted upon said yoke, an endless band movable through said recess and provided with lugs adapted to contact with the rounded projection of the latch, the latter being provided with a 35 downwardly projecting portion, and spring-pressed selector bars movable in the paths 40 of said rounded projection of the latch and said pawl, the latter adapted to turn idly over the selector bar as the pawl moves in one direction and the latch designed to be released by contact with the selector bar, 45 thus allowing the carriage to return under spring action to a limit determined by the pawl coming in contact with the selector bar on its return movement.

6. A selector device for checkwriters, comprising a spring-pressed carriage, an endless band with lugs thereon at intervals, sprocket and pulley wheels about which said band travels, means for operating said sprocket wheels, a yoke adapted to be connected to the carriage of the checkwriter and having a lateral projection, a split tube, the projection of said yoke extending into said tube, a spring-pressed pivotal latch and pivotal pawl upon said yoke, selector bars movable 55 in the path of projections of said latch and pawl, the latter adapted to turn idly over the selector bar as the pawl moves in one direction and the latch designed to be released by contact with the selector bar, thus 60 allowing the carriage to return under spring 65

action to a limit determined by the pawl coming in contact with the selector bar on its return movement.

7. A selector device for checkwriters, comprising a spring-pressed carriage, an endless band with lugs thereon at intervals, sprocket and pulley wheels about which said band travels, means for operating said sprocket wheels, a yoke adapted to be connected to the carriage of the checkwriter and having a lateral projection, a split tube, the projection of said yoke extending into said tube, a latch pivotally mounted upon a part of the yoke and having its free end bent to form a rounded projection, pawl pivotally mounted upon the yoke, selector bars movable in the paths of said rounded projection and pawl, the latter adapted to turn idly over the selector bar as the pawl moves in one direction and the latch designed to be released by contact with the selector bar, thus allowing the carriage to return under spring action to a limit determined by the pawl coming in contact with the selector bars on its return movement.

8. A selector device for checkwriters, comprising a spring-pressed carriage, an endless band with lugs thereon at intervals, adapted to engage and move said carriage against the tension of its spring, sprocket and pulley wheels about which said band travels, means for operating said sprocket wheels, a yoke adapted to be connected to the carriage of the checkwriter and having a lateral projection, a split tube, the projection of said yoke extending into said tube, a latch pivotally mounted upon a part of the yoke and having its free end bent to form a rounded projection, a pawl pivotally mounted upon the yoke, plates spaced apart, and selector 100 bars movable between said plates and in the paths of said pawl and rounded projection, said pawl adapted to turn idly over the selector bar as the pawl moves in one direction and the latch designed to be released by contact with the selector bar, thus allowing the carriage to return under spring action to a limit determined by the pawl coming in contact with the selector bar on its return movement.

9. A selector device for checkwriters, comprising a spring-pressed carriage, an endless band with lugs thereon at intervals, adapted to engage and move said carriage against the tension of its spring, sprocket and pulley wheels about which said band travels, means for operating said sprocket wheels, a yoke adapted to be connected to the carriage of the checkwriter and having a lateral projection, a split tube, the projection of said yoke extending into said tube, a latch pivotally mounted upon a part of the yoke and having its free end bent to form a rounded projection, a pawl pivotally mounted upon the yoke, plates spaced apart, se- 125 130

lector bars movable between said plates and in the paths of said pawl and rounded projection, said pawl adapted to turn idly over the selector bar as the pawl moves in one direction and the latch designed to be released by contact with the selector bar, thus allowing the carriage to return under spring action to a limit determined by the pawl coming in contact with the selector bar on its return movement, pins projecting from said selector bars and movable through slots

in one of said plates, a spring fastened to said pin and to the plates and normally holding the bars out of the path of said pawl.

15

In testimony whereof I hereunto affix my signature in presence of two witnesses.

JOHN B. DENNIS.
